LOADING MACHINE

Forrest D. Grim, Allentown, Pa., assignor to Trojan Powder Company, a corporation of New York

Application February 3, 1942, Serial No. 429,355

2 Claims.

(Cl. 86—29)

This invention relates to a machine for pressing compositions into containers and particularly to a machine for pressing a charge in convenient manner into a container provided with a threaded mouth while protecting the threads of the container against fouling by the charge and also preventing escape of the charge around the pressing element of the machine.

The machine is especially adapted for use in pressing the bursting charge into a shell such as the Oerlikon anti-aircraft shell. The machine will be illustrated, therefore, by detailed description in connection with filling the Oerlikon shell and in connection with the attached drawing, to which reference is made.

The invention comprises the herein described arrangement and combination of coacting parts including a punch adapted to press the charge into the selected container, a guide member disposed around the punch and adapted to extend at one end into the charging end of the container to be filled and to maintain the alignment between the guide member and the punch, spring pressed means for forcing the guide member at its forward portion into the container as the punch of the machine is moved in the direction of the charge to be compressed, a guide collar disposed outside the said guide member and adapted to contact the outside of the charging end of the container and thus center the apparatus with respect to the container as the movement of the punch in the direction of the charge is initiated, and spring means for forcing the guide collar firmly but yieldably against the outside of the charging end of the container.

In the drawing

Fig. 1 is a vertical sectional view of the machine as being used in pressing the charge downwardly into a shell.

Fig. 2 is a sectional view on line 2—2 of Fig. 1.

In the drawing there is shown an Oerlikon 20 mm. anti-aircraft shell 10 standing upright with explosive charge 12 disposed within the shell. The shell is provided with the charging end having an interiorly threaded mouth 14 and a shoulder 16 that is below the threaded portion and is spaced somewhat from the threaded portion. The shoulder defines an annular space of somewhat smaller diameter than the diameter of the threaded portion.

The machine includes the pressing plunger or punch 18 of diameter and shape to fit within the shell without striking the shell. Disposed around the punch is the guide member 20 which, at its end that is downward when the machine is in

use, is adapted to extend within the threaded mouth of the shell and sufficiently therebelow to contact the shoulder 16 extending completely around the shell, while leaving a small space above the upper part of the threaded mouth of the shell. Coil spring 22 rests upon the upper part of this guide member, is disposed around the punch and contacts at its upper end the spring stop 24 that may be in the form of a ring, with set screw 26 holding the ring to the punch.

To center the apparatus with respect to the shell when the movement of the plunger in the direction of the charge is first begun, there is used a guide collar 28 having a lower part that is shaped to conform approximately at least with the charging end of the shell. This guide collar is mounted slidably on union 30 which, in turn, is attached at one end, as by threads, to the said guide member 20 and at the other end to a bushing 32 disposed above the said spring stop 24 and around the punch 18. The guide collar is held non-rotatably around this union 30 by means of set screws or bolts 34 which ride in slots 36 in the said guide collar 28.

The punch is centered by the construction shown with respect to the guide member 20 and the outer collar 28.

Disposed above the guide collar and around the union is a coil spring 38 and above the spring a stop or bearing ring 40 which is maintained in fixed relationship to the union 30 as by threads engaging the union.

The spring 22 is preferably somewhat stiffer than the spring 38, so that, when the plunger movement downward is first initiated, the centering collar 28 is moved downwardly and firmly against the charging end of the shell, so as to center the apparatus, the spring 22 then moving down the thus centered guide member 20, so that the guide member forms a sealing contact with the shoulder and the charging end of the shell is engaged firmly in the annular space defined between the said guide collar and the guide member, the guide member and guide collar, after 45 the completion of the movement of each, being maintained by the assembly shown in approximately fixed spacing from each other.

Pressure upon the punch is obtained by mounting the punch on the ram of a conventional press (not shown).

For operation, a suitable support such as a table or bench (not shown) is provided for the shell and the machine is mounted thereabove at such an elevation that when pressure on the springs 22 and 38 is released, the shell may be

forced on the support and directly under the machine. As the plunger is forced down by the press, the guide collar 28 is moved downwardly, under the spring pressure, against the outside of the upper part of the shell, so that the shell is exactly centered with respect to the machine. As the plunger 18 moves farther down, the spring 22 presses the inner guide member downward so that the forward end of the said member contacts the shoulder within the charging end of the shell. This forward portion of the guide member is suitably of somewhat smaller internal diameter than the diameter of the portion of the shell below the shoulder, so that the plunger is prevented from striking any part of the shoulder or the inside of the shell.

The explosive charge that has been placed within the shell in advance of the operation described may be in loose form, but is preferably in pretableted condition.

As the punch comes down upon the explosive charge, the charge is consolidated and caused to conform to the shell space below the punch, the dusting up or forcing of the explosive charge under pressure against the threads of the mouth of the shell being effectively avoided by the spring pressed contact of the guide member 20 against the shoulder 16 of the shell. As a result there is decreased the work required in cleaning the threads after the explosive charge is compressed, and also there is decreased the danger of premature explosion on screwing in the nose of the shell (not shown) after the shell is filled with the bursting charge.

When the punch or plunger has been brought down to the desired extent, as shown, for example, by the pressure recorded on a standard gage on the press (not shown), the pressure is released and the ram of the press with attached punch is raised, whereupon a slight lifting action applied manually to the guide collar 28 causes movement of the machine away from the shell so that the shell may be removed from its position on the support and a fresh shell with charge to be compressed inserted under the machine.

It will be understood that other containers into which charges of powdered, granular, or tableted compositions are to be compressed may be substituted for the Oerlikon shell described. It will be understood also that the guide collar and parts operating therewith may be omitted from the machine if the centering and stiffening effects obtained by the use of the collar are not desired. Particularly satisfactory results, as to convenience, accuracy of operation, and firm seating of the apparatus upon the container to be filled are obtained, however, by the use of the guide collar and the spring element 38 which forces the guide collar into conformance with the upper part of the container.

Materials of construction of the machine are those which are usual in machines of the general class of the present one. Thus, brass, stainless steel, bronze, or like metals are satisfactory, met-

als or alloys that do not form sparks on striking being preferred when the charge is one that may be ignited by a spark.

It will be understood also that certain details given are for the purpose of illustration, not restriction, and that variations within the spirit of the invention are intended to be included within the scope of the appended claims.

What is claimed is:

10. A machine for pressing a charge in a rigid container having a charging end provided with an interiorly shouldered wall and a mouth opening upwardly during the pressing operation, the machine comprising a punch serving as the pressing unit upon the said charge; a guide member for the punch fitting around the punch and holding the punch centrally therewithin; an extension of the guide member that at its lower end is smaller in internal diameter than the said mouth at its most narrow portion, extends into the said mouth, and fits in sealing relation against the shoulder of the said wall; a coil spring disposed directly around the punch and resting upon the said guide member; a spring stop mounted upon the punch at a position above the guide member and engaging the top of the said spring; a guide collar for the container mounted slidably and centrally around the said guide member, the guide collar defining with the guide member a generally annular space to receive the charging end of the container; a second coil spring weaker than the first spring resting upon the guide collar; a second spring stop mounted upon the guide member at a position directly above the second spring; and means for forcing the punch downward through the guide member and upon the charge in the container; the downward movement of the punch compressing the second spring, causing the guide collar to become seated upon the container, applying pressure through the first spring directly upon the punch guide member as the punch continues its downward travel, causing sealing contact of the lower end of the said extension of the guide member with the shoulder of the wall of the container, compressing the first spring, and causing the punch to enter the container.

2. A machine as described in claim 1 adapted for use in pressing an explosive charge in a shell provided with a mouth of threaded interior and having a shoulder disposed inside the shell and below the threaded mouth and encircling an annular opening of smaller diameter than the threaded mouth, the said guide member having a part of smaller internal diameter than the threaded mouth and somewhat longer than the distance between the shoulder and the outer end of the threaded mouth and the said part being adapted to extend through the threaded mouth and to contact the said shoulder in sealing relationship, so as to minimize contact of the explosive with the threaded mouth during pressing of the charge within the shell.
